UNITED STATES PATENT OFFICE.

HENRY THOMSON, OF PERTH, WESTERN AUSTRALIA, AND WILLIAM R. OYSTON, OF KENSINGTON, NEAR SYDNEY, NEW SOUTH WALES, AUSTRALIA; SAID OYSTON AS-SIGNOR TO SAID THOMSON.

PIANO PLAYER.

Application filed November 18, 1920. Serial No. 424,810.

To all whom it may concern:

Be it known that we, HENRY THOMSON, residing at Perth, in the State of Western Australia, Commonwealth of Australia, and 5 WILLIAM ROBERT OYSTON, residing at Kensington, near Sydney, in the State of New South Wales, Commonwealth of Australia, both subjects of the King of Great Britain, have invented new and useful Improvements 10 in and Relating to Piano Players, of which the following is a specification.

This invention relates to improvements in and relating to piano-players and refers more particularly to a pneumatic player attachment adapted to be applied to an ordinary piano without any structural alteration to the latter, and which may be readily placed in or out of action without interfering with the means for manually operating 20 the instrument.

In applying known player apparatus to an existing piano it is customary to have the player actions and auxiliary mechanism built into the frame of the instrument and 25 arranged to operate the actions thereof. This usually necessitates the transportation of the piano to a workshop properly equipped to enable the performance by skilled workmen of a series of highly technical operations. In addition it is generally necessary to radically alter the construction 30 of the instrument requiring the exercise of exceptional skill to avoid deterioration of the piano considered as a manually playable instrument.

It is customary in keyboard piano-player attachments or devices to employ lever actions for the purpose of transmitting to the key-strikers the motion derived from ordinary pneumatics. The use of the ordinary 40 perforated roll system of player control necessitates the employment of a moderate "pull" in inches of vacuum which, however, is insufficient to directly operate the key-strikers.

It is an object of the invention to provide a pneumatic player of small compass adapted to be readily fitted to a piano with a minimum of skill without requiring structural alteration of the instrument and 50 wherein the key-strikers are direct acting, dispensing with intervening levers or other known actions, and are operated by the creation of a vacuum at required points.

Another object of the invention is to provide in a piano-player improved means whereby the key-strikers are operated by a vacuum system controlled with suitable valves by the admission of air through the slots of a music roll and wherein all the 55 operating pneumatics are arranged in a single row. Foot-operated exhauster bellows maintain a constant vacuum in a vacuum chest which may be placed selectively by suitable valves in communication with the 60 collapsible pneumatics, thereby operating key-strikers attached to said pneumatics.

A further object of the invention is to provide operating pneumatics of improved construction and each formed integrally as a 70 unit with a control valve casing.

The invention further provides in a piano-player improvements in exhauster bellows and in folding pedal operating mechanism.

With these and other objects in view the invention consists of the features of construction, combination and arrangement hereinafter fully described, reference being had to the accompanying drawings wherein:

Figure 1 is a view in front elevation of a 80 piano fitted with the player attachment, the latter being in its operative position.

Figure 2 illustrates in side elevation the player attachment operatively mounted on a piano and indicating by broken lines its 85 inactive position.

Figure 3 is a plan, partly in section, of a tubular supporting bracket.

Figure 4 is a side elevation of the tubular supporting bracket and its locking devices— 90 broken lines indicating the positions occupied when the player attachment is placed into its inactive position beneath the keyboard of the pianoforte.

Figure 5 is a part front elevation of the 95 tubular supporting bracket and its locking devices.

Figure 6 is a front elevation of the foot-motor comprising vacuum and reservoir exhausters.

Figure 6^a is a sectional front elevation of 100 the foot-motor.

Figure 7 is a vertical cross-section taken on line *a*—*a* of Figure 6.

Figure 8 is a side elevation of the foot-motor and the operating folding pedals.

Figure 9 is a view in plan of the pedals and pedal mechanism.

Figure 10 is a side elevation, and Figure 11 is a view in plan of a metal cheek plate of an exhauster bellows.

Figure 12 is a vertical section taken on the line *b*—*b* of Figure 11.

Figure 13 is a view in plan of a roller bearing for the operating spindle of an exhauster bellows.

Figure 14 is a sectional elevation of the roller bearing.

Figure 15 is a view in side elevation, partly in section, illustrating the vacuum chest, portion of a pneumatic, control valve and key-striker.

Figure 16 is a view similar to Figure 15 but illustrating more particularly the arrangement of control valves in relation to the single row of pneumatics.

Figure 17 is a view in plan illustrating the arrangement of pneumatics and their control valves.

Figure 18 is a view in plan of a diaphragm cap seating with tube coupling.

Figure 19 is a perspective view of a valve. In these views a pneumatic action-chest or casing 20 preferably constructed of wood of approved design and finish constructed and arranged to extend approximately the whole length of the keyboard of the piano.

Mounted in alignment and in a single row in the action chest are collapsible pneumatics 21 corresponding numerically to the keys of the piano.

Pneumatics as commonly employed for the purpose of operating piano playing actions are of the leaf type and comprise plates hinged together and connected by flexible material such as soft leather. These constructions have the disadvantage of being somewhat bulky and of requiring considerable space to work in when the power required to be exerted is of any magnitude.

The pneumatics employed in this invention are of small size and require only small working space, whilst they are capable of exerting sufficient power when the contained air is exhausted therefrom to operate directly upon the keys of a piano, thereby dispensing with lever mechanisms.

Each pneumatic comprises a stationary base plate 22 surmounted by two floating plates 23 and 24, the intervening spaces between said plates being enclosed by an envelope 25 of animal membrane folded or creased so as to permit of the two floating plates collapsing close to the base plate 22 in concertina manner.

Strips 26 of soft leather are affixed to the pneumatics and prevent injury thereto by abrading action of the stems of attached key-strikers during the collapsing actions of the pneumatics.

Each of the key-strikers comprises a stem 27 of strip metal having its upper end bent inwardly whereby it is conveniently bent

over and secured as by a screw 28 to the top floating plate 24 of its operating pneumatic. The lower end of the stem 27 passes through a slotted guide block 29 secured to the underside of the base plate 22 of the pneumatic and is bent inwardly and downwardly in order that the striking tip 30 of resilient material secured thereto is positioned in central relationship with its operating pneumatic.

The control valves associated with pneumatics employed in player-pianos are ordinarily constructed of separate entities and are built into specially designed and constructed casings.

We provide an operating pneumatic and control valve casing of unitary construction. The base plate 22 of each pneumatic is of light metal such as aluminium and is formed integrally with the valve casing 31. An air passage 32 connects the interior of the pneumatic 21 through the base plate 22 with the interior of said valve casing. The latter is constructed with a flange 33 for attachment as by means of a screw 34 to the casing 35 of the main vacuum chamber 36 located longitudinally in the action chest 20.

The valve casing 31 is cored or machined out so as to form two chambers 37 and 38 with a divisional wall 39 having a central orifice 40.

The upper chamber 37 has a detachable retaining cap 41 having an air inlet 42. The orifice 40 in the wall 39 forms a valve seat for a valve 43 having a stem 44 extending into the lower chamber 38. Across this lower chamber 38 there is secured a flexible diaphragm 45 of greater diameter than that of said valve 43.

Detachably fastened by a screw to said valve casing 31 below the diaphragm 45 is a diaphragm cap seating 46 in which is formed a shallow recess 47. An outlet passage 48 is formed in said cap seating so that said shallow recess communicates with a nipple 49 to which is connected a flexible tracker tube 49^a leading from one of the air-ducts of the tracker-bar.

The lower chamber 38 in the valve casing is connected by an exhaust passage 50 to the main vacuum chamber 36. A small vent or bleed hole 51 connects the passage 48 with the exhaust passage 50 leading from the lower chamber 38 of the valve casing to the main vacuum chamber 36 and a pin 52 is adjustably fitted into said vent for the purpose of regulating the area thereof.

This vent 51 is to enable the tracker tube 49^a connected to the nipple 49 to be pneumatically exhausted. A slight suction is thus created in the tracker tube sufficient to exhaust the air therefrom when covered by the music sheet and prevent the operation of the valve 43, but insufficient to exhaust it when uncovered by the music sheet.

This suction also tends to hold the music sheet in close contact with the tracker-bar.

The constant suction exerted on the underside of the valve 43 maintains the latter firmly on its seat except at such times as a slot in the music sheet passes over a duct in the tracker-bar, when an influx of air takes place and enters the recess 47 beneath the diaphragm 45. The diaphragm has an area 10 greater than that of the underside of the valve 43, and in consequence the pressure of air, so admitted, overcomes the outside air pressure on the valve which is raised, motion being communicated thereto through 15 the valve stem 44. Thereupon the valve is raised from its seat closing the air inlet 42, when the confined air is exhausted from the pneumatic 21 through the passage 32, orifice 40 and passage 50, the latter communicating with the vacuum chamber 36.

Upon the exhaust of the contained air from the pneumatic 21, the two floating plates 23 and 24 thereof are collapsed suddenly downwardly, causing the key-striker 25 30 to strike a blow on a key of the piano.

When the duct in the tracker-bar is closed by a blank portion of the music sheet, the suction exerted on the underside of the diaphragm 45 and communicated thereto 30 through the passage 50 and the vent 51 draws the valve 43 back onto its seat thus opening the air inlet 42 and admitting outside air into the pneumatic 21 through the passage 32 and expanding it in readiness for its next operation.

The operating pneumatics 21 for the key-strikers are constructed of a required width such as will permit of their arrangement in a single row within the action chest 20 and in 40 such manner that when the player attachment is placed in its operative position said pneumatics are directly above the piano keys.

This feature is of special importance structurally and for efficiency in operation. It 45 permits the direct action of the strikers on the keys of the instrument without requiring the employment of combination of lever actions and to obtain blows of required force 50 onto the keys, while there is obtained the additional advantage of economy of space in the action chest 20, thus enabling the player attachment to be constructed in a very compact and simple manner.

The valve casings 31 are of greater diameter than the width of the pneumatics 21. As a consequence, the air passages 32 leading from alternate valve casings to the pneumatics are downwardly inclined from the 60 latter as illustrated in Figure 15, while the air passages 32 leading from the intermediate valve casings are inclined upwardly from the base plates of the pneumatics as is illustrated in Figure 16.

Said valve casings of the one series are

thus arranged at a higher level than those of the other or intermediate series, while all of said valve casings are positioned in centrally longitudinal alignment as is shown in Figure 17, thereby facilitating the arrangement 70 of operating pneumatics in a single row directly above the keys of the piano for the purposes described.

A spool box 53 is surmounted on the action chest 20 and it is provided with conventional equipment of spring-pressed supports for music roll, take-up roll, tracker bar and tracking device as ordinarily employed in the art.

At one end of said spool-box there is a casing 54 enclosing spool-motor and rewind mechanism which may be of known construction, while expression controls 55 and "tempo" control 56 of standard construction are also provided.

Plates 57 are secured by means of screws to the underside of the keyboard. These plates are constructed with downwardly projecting lugs 58 in which are formed bearings 59. Pivotaly mounted in said bearings 90 are tubular trunnions 60 and 61 formed on either side at the lower end of a bracket 62 adjustably supporting the action chest 20.

Brackets 63 are suitably secured to the action chest 20 and have bearings 64 formed 95 therein receiving tubular trunnions 65 and 66 formed on either side at the upper end of said supporting bracket 62.

This action-chest supporting bracket 62 is preferably of cast metal and of bent or 100 curved formation. It is constructed with tubular passages 67 and 68 in uninterrupted communication with the trunnions 60 and 65 and with the trunnions 61 and 66, respectively.

The trunnions 60 and 61 are fitted with swivel couplings 69 of approved construction to which are connected tubes 70 communicating with the vacuum reservoir of the foot-motor hereinafter described.

The trunnion 65 is swivelly coupled with a tube 71 communicating with the main vacuum chamber 36 located in the action chest 20, while the opposite trunnion 66 is connected by tubing 72 with the spool-motor 115 located in the casing 54.

The bearings 64 of the brackets 63 have forwardly projecting and apertured lugs 73, in which is rotatably mounted a rocking bar 74 around one end of which is wound a tension spring 75.

A latch 76 having a finger-operating piece 77 is fixedly secured to the rocking-bar 74 and is adapted to engage automatically with either of two holes 78 and 79 formed in vertical alignment in the face of the action-chest supporting bracket 62. Said latch enters the upper hole 78 when the player attachment is placed in its raised operative position, and enters the lower hole 79 when 130

placed in its lowered or inactive position on the piano, thereby automatically locking the player attachment in either of its set positions.

5 To the underside of said tubular bracket 62 there is secured a spring-actuated latch 80 adapted to take into a hasp 81 secured to the underside of the keyboard when the player attachment is placed in its inactive 70 position, as illustrated by broken lines in Figures 2 and 4, and thereby prevent accidental displacement of said attachment.

10 The foot-motor 72 comprised in the invention is fitted by means of brackets 82 within 15 the lower front portion of the piano case without necessitating structural alteration thereto. To this end there are provided a vacuum reservoir 83 and a pair of exhauster bellows 84, the latter being arranged on opposite sides of said vacuum reservoir.

15 The stationary back members of the vacuum reservoir 83 and the exhauster bellows 84 are rigidly secured to top and bottom supporting rails 85 and 86.

20 25 A longitudinal channel 87 is formed in the top supporting rail 85 and is in communication with the interior of the vacuum reservoir 83 by the port 88 and with the interior of the exhauster bellows 84 by the ports 89, 30 the latter being fitted with non-return valves of approved design.

25 35 The movable member of the vacuum reservoir 83 is designed to operate radially from its hinged upper end in an up and down direction while the movable members of the exhauster bellows 84 are so designed and hinged to the stationary members that they operate in a horizontal plane. These 40 movable members are furnished with air outlet ports 90 fitted with non-return valves of approved design.

45 Pipes 91 are fitted to the top supporting rail 85 and lead to the channel 87. These pipes receive the ends of the tubular connections 70 which communicate with the passages 67 and 68 of the bracket 62 supporting the action-chest 20.

50 The construction of the foot-motor described is compact enabling it to be fitted readily within the case of any standard sized piano.

55 A metal cheek-plate 91' is secured to the movable member of each exhauster bellows 84 and it has at its lower end an apertured clamping lug 92.

60 Rigidly connected to the back stationary member of each exhauster bellows 84 is an inwardly projecting arm 93, while similarly shaped arms 94 extend inwardly from the cheek-plates 91'. A bow-shaped spring 95 is arranged between said arms 93 and 94, the lower end of the spring members being detachably fastened to said arms. The purpose of these springs 95 is to produce the return motion of the exhauster bellows 84 fol-

lowing the opening of the same, and also to produce the return stroke of the pedals by the transmission of motion thereto through vertical spindles 96, crank-levers 97 and push-rods 109.

70 Return-motion springs 98 are also employed to control the actions of the movable member of the vacuum reservoir 83.

75 The vertical spindles 96 are securely retained in the lugs 92 formed on the cheek-plates 91' by means of clamping bolts 99. Each of said spindles 96 engages with a pair of horizontally arranged disc rollers 100 loosely fitted in a semi-circular race 101 formed in a housing 102 which latter is secured by screws to the floor of the piano case. The function of these rollers is to provide a thrust-bearing for said spindle and to prevent any oscillatory movement thereof when the pedals are in action. Stop pins 103 are fitted into said housing to prevent dislodgment of said rollers from the race 101.

80 85 The crank-levers 97 are fixedly secured to the lower ends of the vertical spindles 96 by means of set-screws 104. The upper end of each vertical spindle is formed with a gap 105. An adjusting screw 106 is fitted to the clamping lug 92 and projects within said gap a required distance to permit the vertical spindle to be partially rotated in order to adjust the setting of the crank-lever 97, to obtain required pedal efficiency, and the clamping bolt 99 is then tightened to lock the spindle in its adjusted position.

90 95 Each crank-lever 97 has a V-shaped slot or bifurcation 107 (Fig. 8) in its free end which receives the curved end 108 of the push-rod 109 hingedly connected at 110 to the pedal 111. A coiled spring 112 serves 100 to maintain the end of said push-rod in engagement with said V-shaped slot.

100 105 The pedals 111 are hingedly mounted upon pintles 113 which project laterally from a U-shaped supporting frame 114, the side members of which are hingedly connected to brackets 115 which are fixedly mounted on the lower front portion of the piano case. The pedal supporting frame 114 is formed 110 with feet 116 which are shod with pads 117 115 of rubber or like resilient material.

110 115 By reason of the resilient engagement of the ends of the push-rods 109 with the slotted ends of the crank levers 97, a pivotal driving engagement is maintained, while permitting the pedal supporting frame, pedals and push-rods to be folded upwards closely against the face of the piano case, in which position they are retained by their own weight.

115 120 A player attachment according to the invention and fitted to an ordinary piano assumes the position illustrated by broken lines in Figure 2, the action chest 20 being located under the keyboard and the pedals 111 folded against the front of the instru-

ment case, when the piano may be manually operated in the usual manner.

In order to place the player attachment into its operative playing position, the latch 58 is released from the hasp 81 and the tubular curved bracket 62 supporting the action chest 20 with attached spool-box 53, motor casing 54 and contained mechanisms is swung radially until said action chest is positioned directly above the keyboard, when it is automatically locked in position by the entrance of the latch 76 into the upper hole 78 formed in said bracket 62. The pedal mechanism is unfolded until the pads 117 rest firmly upon the floor.

Pedal action by the operator actuates the foot-motor, the exhauster bellows 84 of which create and maintain a vacuum in the vacuum chamber 36 in the action chest 20 through the flexible tubular connections 70 in communication with the passage 67 formed in the curved bracket 62. The same pedalling action operates the spool propelling motor in the casing 54 by means of the connections from the foot-motor through the passage 68 in said bracket 59 and communicating trunnion passage 66.

What we do claim is:—

1. In piano player apparatus, a chest having a vacuum chamber, a series of operating pneumatics corresponding in number to the keys of the keyboard of a piano, said pneumatics being connected to the vacuum chamber and arranged in a single longitudinal row in parallel relation; and means to support the chest upon the piano casing with the pneumatics above the piano keys.

2. In piano player apparatus, a chest having a vacuum chamber; a series of operating pneumatics corresponding in number to the keys of the keyboard of a piano connected to the vacuum chamber and arranged in a single longitudinal row in parallel relation, each pneumatic comprising a fixed plate, floating plates arranged parallel above the fixed plate and a flexible envelope for the plates; means to support the chest upon a piano case with the pneumatics above the keys; and strikers connected to the movable plates of the pneumatics.

3. In piano-player apparatus, an action chest and a bracket for pivotally supporting said action chest, said bracket having tubular trunnions projecting through opposite sides adjacent opposite ends thereof and having tubular passages each in communication with a pair of said trunnions.

4. In piano-player apparatus, an action chest: a main vacuum chamber, operating pneumatics and control valves in said chest: a spool-box and spool-motor mounted on said chest, a supporting bracket for said chest, tubular trunnions on opposite sides of and at the upper and lower ends of said bracket, bearings secured to the piano case pivotally

receiving said lower trunnions, bearings on said action chest receiving said upper trunnions, tubular passages in said bracket each communicating with one upper and one lower of said trunnions, connections from 70 said upper trunnions to the main vacuum chamber and to the spool-motor, and exhaust means for connection with said lower trunnions to a foot-motor.

5. In piano-player apparatus, an action 75 chest fitted with a main vacuum chamber, operating pneumatics having valve controlled connections with the vacuum chamber, key-strikers fixed to said pneumatics, spool and spool-propelling mechanisms 80 mounted on said chest, exhaust means including a vacuum reservoir and exhauster bellows, folding pedal mechanism operatively connected to said exhauster bellows, a supporting bracket for said chest, tubular trunnions on opposite sides of and at the upper and lower ends of said bracket, bearings secured to the piano case pivotally receiving said lower trunnions, bearings on 85 said action-chest receiving said upper trunnions, tubular passages in said bracket each communicating with one upper and one lower of said trunnions, connections from 90 said upper trunnions to the main vacuum chamber and to the spool-motor, connections 95 from said lower trunnions with the exhaust means, and means for locking said action-chest in its operative position directly above the keyboard, and in its inactive position beneath said keyboard.

6. In piano-player apparatus, an action-chest carrying a main vacuum chamber, operating pneumatics, control valves for said pneumatics and key-strikers actuated by said pneumatics: a spool-box and motor-casing 105 surmounted on said action-chest, a curved or bent bracket operatively supporting said chest directly above the piano keyboard, bearings fitted to said chest pivotally receiving the upper end of said bracket, means on 110 said bearings rotatably supporting a rocking lever, a tension spring on said lever, bearings fitted to the piano case beneath the keyboard pivotally receiving the lower end of said curved bracket and a latch on said 115 lever forming a locking engagement with said curved bracket when said action-chest is placed either into its operative or into its inactive position.

7. In piano-player apparatus, a foot-motor 120 comprising, a vacuum reservoir, a pair of exhauster bellows, means for the fixture of the stationary members of said reservoir and said bellows, arms on said stationary members, means whereby the hinged movable member of said reservoir operates in an up and down direction and the hinged movable members of said exhauster bellows operate in a horizontal plane, cheek-plates fitted 125 to the movable members of said exhauster 130

bellows, arms on said cheek-plates, return-motion springs fitted between each set of arms of said exhauster bellows, and return-motion springs controlling the motions of said

5 reservoir.

8. In piano-player apparatus having a main vacuum chamber and spool-motor mechanism, a foot-motor comprising, top and bottom supporting rails, a vacuum reservoir, and a pair of exhauster bellows having their rear members affixed to said rails, a channel in the top rail communicating with said reservoir by means of a port and in communication with said exhauster bellows by means of ports, non-return valves fitted to the latter ports, pipes fitted to said rail and communicating with said channel, tubular connections from said pipes to the main vacuum chamber and spool propelling

20 motor, and return motion springs fitted to said reservoir and to said exhauster bellows.

9. In piano player apparatus, the combination with vacuum creating means, of a series of pneumatics arranged in a longitudinal row in parallel relation and having key strikers connected thereto, and means to connect said pneumatics with the vacuum creating means and adjustably support the same to extend above the keyboard of the piano

25 and to be swung to position below the keyboard.

10. In piano player apparatus, the combination with vacuum creating means, of a series of key striker actuating pneumatics, and means to connect said pneumatics with the vacuum creating means and support the pneumatics to be adjusted to position to extend above the keyboard of the piano or to position below the keyboard.

40 11. In piano player apparatus, the combination with vacuum creating means, of a chest having a vacuum chamber; a series of key strikers actuating pneumatics mounted upon said chest in communication with

45 the vacuum chamber and to extend laterally

of the chest; and a bracket to support the chest to have adjustment to position with the pneumatics extending longitudinally above the keyboard of a piano and adjusted to position below the keyboard and to connect the vacuum chamber with the vacuum creating means.

50

12. In piano player apparatus, the combination with vacuum creating means, of a chest having a vacuum chamber; a spool and spool motor carrying box mounted upon the chest; a series of key striker pneumatics mounted upon the chest to extend laterally thereof and in communication with the vacuum chamber; a pivotally supported bracket pivotally connected to the chest, said bracket having a pair of chambers both of which are connected to the vacuum creating means with one chamber connected to the spool motor and the other to the vacuum chamber, said bracket being adjustable to support the chest in position with the pneumatics above the keyboard and in position below the keyboard; and means to releasably retain the bracket and chest in either of

55

60

70

75

13. In piano player apparatus, a chest having a vacuum chamber arranged for connection to vacuum creating means; control valve casing mounted on said chest in communication with the vacuum chamber; pneumatics carried by said casings in a longitudinal row in parallel relation to each other; a spool box and spool motor mounted on said chest, said chest with the spool box and motor and valve casings with the connected pneumatics mounted thereon being constructed and arranged as a unit.

In testimony whereof we affix our signatures in presence of two witnesses.
